UNITED STATES PATENT OFFICE.

PERRY S. MARTIN, OF HARRISONBURG, VIRGINIA, ASSIGNOR TO THE KERVAN COMPANY, OF NEW LONDON, CONNECTICUT, A CORPORATION OF CONNECTICUT.

MACHINE FOR CLEANING EGGS.

Application filed April 12, 1924. Serial No. 706,047.

This invention relates to machines for cleaning eggs, but more particularly has reference to machines of this description that employ a sand blast as a cleaning agent.

5 In the cleaning of eggs, it is usual to first remove all lumpy and prominent foreign matter from the eggs by any well known means, preparatory to subjecting the eggs to the general cleaning operation, and this is 10 what is done in the present instance.

While this invention employs a sand blast as a cleaning agent there is no novelty claimed herein, in a broad sense, for the cleaning of eggs by a sand blast, since such 15 a process is well known and has been heretofore practiced with more or less success.

But heretofore, in the cleaning of eggs by a sand blast, the process has been comparatively slow and expensive, owing to the manner in which the blast is obtained, and for the further reason that it has been found exceedingly difficult to get rid of the sand after the latter has once performed its function.

25 The chief object of the present invention is to so create and direct the sand blast that it may perform its function in a very rapid and efficient manner, after which it is disseminated, and while in this state is acted upon by an air blast which latter drives the sand away from the eggs and the surrounding parts and causes the sand to be eventually delivered back into the hopper with the dust and dirt particles removed therefrom so that clean sand always operates against 30 the eggs.

In the above connection stress is also laid upon the fact that the air blast and the manner in which it is created, controlled and directed are the main features of this invention.

In the accompanying drawings which form a part of this application:—

Figure 1 is a front elevation, partly broken away, of one form of machine for carrying out this invention.

Figure 2 is a section at the line 2—2 of Figure 1—

Figure 3 is a detail section at the line 3—3 of Figure 2—

Figure 4 is a detail section at the line 4—4 of Figure 2—

Figure 5 is a detail section at the line 5—5 of Figure 2—

Figure 6 is a section, partly broken away, 55 at the line 6—6 of Figure 1—

Figure 7 is a section, partly broken away, 60 at the line 7—7 of Figure 2—

Figure 8 is a detail sectional elevation of the egg supporting platform with an approved form of rubber mat resting thereon—

Figure 9 is a top view, at the line 9—9, of 65 the machine with the cover removed—

Figure 10 is a detail perspective of one of 70 the egg confining and manipulating fingers—

Figure 11 is a detail, broken perspective of one of the gates that flank the front portion of the machine, and

Figure 12 is a section at the line 12—12 75 of Figure 1.

Similar numerals of reference denote like parts in the several figures of the drawing.

In the description of this invention no stress whatever will be laid on details of 75 construction or assembly of parts that relate to the mere enclosure of the essential elements, or to the securing of such parts in proper and conventional relation, but endeavor will be made to confine this description to the elements and functions of parts 80 that are actually necessary to bring about the results aimed at by the invention.

Since the machine must have some sort of supporting structure and some approved 85 construction for enclosing the operative parts, the general supporting structure is designated by the numeral 1 while the general enclosing structure is identified by the numeral 2. A circular baffle structure 3 features as the base portion of the machine and is supported by pillars 4 mounted on the support 1. This structure 3 is curved outwardly and inwardly so as to form a baffle wall 5 that overhangs the annular egg supporting platform hereinafter described, and the bottom of this structure has a circular opening 6 having a rim 7, and said bottom has also a concentric series of openings 8 outside said rim. 9 is an ordinary damper plate journaled around the rim 7 and having therein a concentric series of openings 10, said plate being confined in position by keepers 11 secured to the bottom of the part 5, and provided with a suitable handle 12 whereby said plate may be rotated to cause 100 the openings 10 to register more or less with the openings 8 or to close the latter alto- 105

gether, as may be desired, and for the purpose presently to be described.

13 is a conventional electric motor whose shaft 14 is rigid with the hub 15 of a centrifugal sand and air blast member 16. This member 16 is an open flaring structure having spaced radial ribs 17 on its upper surface, whereby the sand is held as against swirling and is discharged centrifugally, while near the outer portion of its lower surface said member 16 has depending spaced and radially extending vanes 18 which function, during the revolution of said member, to create a suction of air so that the latter may be in the nature of a blast centrifugally delivered as will herein-after be particularly described.

This blast member 16 has its lower portion depending through the opening 6 and substantially closes the latter, and the bottom face of this member, throughout the major portion of said face, is suitably spaced from the wall of the structure 3 and has the vanes 18 aforesaid depending therefrom as described.

From the foregoing description it will be readily understood that, when the motor 13 is rapidly revolving, any sand within the member 16 will be impelled therefrom by centrifugal force, while at the same time the air that is permitted to enter the space between the bottom of said member and the wall of the structure 3, will likewise be impelled by centrifugal force.

35 The invention aims to direct this sand blast and to cause the dissemination of the same after it has performed its function, and also to direct the air blast so that it will act against the disseminated sand and drive the latter away from the egg supporting and manipulating elements, and eventually effect the delivery of the sand back into the impeller element 16, and the description immediately following will be made with the especial end in view that a clear understanding may be had of the respective functions of these sand and air blasts.

19 is an annular platform made of cast metal and supported at suitable locations by the upper ends of the pillars 4, as shown in one instance at Figure 5. This platform is stationary, and loosely placed on it is a rubber mat 20, and immediately beneath this platform and at spaced intervals are air deflectors 21 cast with the floor of the structure 3 and upstanding therefrom which lead directly to air deflectors 21^a that are secured to the side portion of the inner wall of the structure 3 and extend inwardly from said portion so as to project from the baffle wall 5.

In the immediate vicinity of the platform 19, and preferably above the same and outside the vertical plate of the outer periphery of said platform, is an annular gear 22

which is supported at suitable intervals by rotary bearings 23 journaled in bosses 24 that extend peripherally from said platform, as shown in one instance at Figure 3. One of these supports for this gear 22 is a 70 rotary bearing 25 that is carried by a vertical shaft 26 having a collar 27 that rests upon one of the bosses 24, the upper end of this shaft having fixed thereto a pinion 28 that meshes with the teeth of the gear 22, 75 while the shaft itself depends loosely through the structure 3 and a journal thimble 29 secured thereto and has fixed on its lower end a bevel gear 30 that meshes with a corresponding gear 31 carried by the shaft of a worm wheel 32, which latter in turn is in mesh with a worm 33 that loosely surrounds a vertical pin 34 extending from the structure 1 and carries a horizontally disposed large pulley 35 that is 85 connected by a belt 36 to a small pulley 37 rigid on the hub 15.

This description of an ordinary form of speed gearing, while rather superfluous, has been made simply for the purpose of establishing premises for the statement that the revolution of the motor is much greater than that of the gear 22; in fact, the motor makes seventeen hundred and fifty revolutions a minute, while the annular gear 22 95 has a speed of but one revolution a minute.

Secured to and extending from any suitable part of this ring 22 are fingers 38 which are located at desired intervals and project above and across the platform 19, and which have angular extensions 39, as shown more particularly at Figures 2, 3, and 12, a detail of one of these fingers being shown at Figure 10.

These fingers are removed from the mat 105 20 by a distance equal to about one-half the shorter diameter of an egg, and the fingers are spaced apart by a distance a little greater than the larger diameter thereof, so that, in effect, separate enclosures or stalls are 110 formed for each egg, the extensions 39 functioning to prevent the eggs from rolling off the rubber mat.

Preferably, short studs 40 project upwardly from the mat 20 at suitable locations 115 for the purpose presently to be explained, but these studs are not of a height sufficient to oppose the fingers 38 when the ring 22 is revolved.

The air blast depends upon the amount of 120 air admitted, by the regulation of the damper 9, into the space between the wall of the structure 3 and the lower face of the blast member 16, and this space leads upwardly beneath the platform 19, and the 125 air blast is accordingly directed against the side and upper portions of the baffle wall 5.

But this air blast directed in this manner has a strong tendency to swirl and it is therefore necessary to provide some means 130

for arresting this swirling action so that such blast may be controlled and directed against the sand after the latter has performed its function and become disseminated by impulsion against the wall 5 or otherwise.

The upper or delivery periphery of the blast member 16 is adjacent the egg supporting platform 19, and therefore it will be readily understood that the sand will be driven against the eggs and will then disseminate, either by reason of contact with the eggs or the members associated therewith, or by striking against the overhanging portion of the baffle wall 5, and more or less of the sand will drop back into the hopper 41 which is suspended by uprights 42 from the wall 5 and has an orifice 43 at the bottom leading to the member 16. But the major portion of the disseminated sand containing dust, incident to the blast, and possibly fine particles of dirt, will be driven by the air blast toward the upper part of the enclosing structure 2, and the manner of controlling this air blast so that it will perform this function will now be described.

When the air blast is delivered from the member 16, such blast will initially strike the deflectors 21, which will materially overcome the tendency of the air to swirl which tendency will be, for all practical purposes, entirely overcome when the air strikes the overhanging deflectors 21^a, and consequently the air blast will be directed inwardly against the disseminated sand and will prevent the latter from falling and banking upon the egg supporting platform, and will also keep the gear 22 and pinion 28 free of sand. As the sand is thus driven by the air blast, some of the sand will drop into the hopper as before explained, but the blast of air, as it seeks an outlet, will carry most of the sand upwardly within the structure 2.

This structure 2 is horizontally partitioned, so as to provide an upper compartment 44 and a lower compartment 45, in the following manner:

Referring to Figures 9 and 12 of the drawing, an annular supporting ledge 46 is secured to the inner, side and back walls of the structure 2 toward the upper part thereof, and a similar ledge 47 is secured to the inner front wall, and on these ledges is supported a sand separator and cleaner 48, which is a drum-like structure whose upper end is closed by a cover 49 that has a circular opening 50 therein, and suspended within this opening is a comparatively small drum 51 which completely fills such opening and depends within the separator 48, the bottom of this drum being composed of a fine screen 52 while the top opens into the upper compartment 44.

The separator 48, near its upper end, has a portion of its body throughout the entire

circuit of the latter, formed by a coarse screen 53, and the lower part of the separator has converging walls with a nozzle 54 at the bottom so that any sand in the bottom part of the separator will be delivered directly into the hopper 41.

The cover 49 is equipped with suitable handles 55 so that the cover may be easily removed, if desired.

When the air blast seeks an outlet it will carry with it the major portion of the disseminated sand together with the sand dust and dirt particles, and the blast thus laden will pass through the coarse screen 53, and thence downwardly, when the sand will fall by gravity into the lower part of the separator 48, but the air, still seeking an outlet, will pass upwardly through the fine screen 52 carrying with it the dust and dirt and will then discharge out through any suitable pipe 56 leading from the upper compartment 44 into the outside air. As the air passes upwardly through the fine screen as just described any sand that is still present will strike this screen, fail to pass through it and drop into the bottom of the separator.

The eggs which are designated by the numeral 57 will have a tendency to adhere to the mat 20 owing to the fact that it is made of rubber, and therefore, the fingers 38 will cause the eggs to roll as they are carried along the circuit of the mat, thus presenting the sides of the eggs to the action of the sand blast, and, although such blast reaches all surfaces of the eggs so that the latter are, as a rule, well cleaned, the fact is recognized that there will be some eggs, whose end surfaces are located at the outer periphery of the mat, that will require a more direct action of the sand blast, and this is provided for as will now be explained.

The studs 40 heretofore referred to are at any desired locations throughout the mat 20, in some instances a single stud being sufficient, and as the eggs are driven along the mat their inner ends will strike the studs, as shown in the instance of the egg marked *x*, and the continued driving action of the finger immediately behind said egg will cause the latter to be turned to the position noted in the instance of the egg marked *y*, so that the further action of said finger will turn the egg completely around so that what was formerly its outer end will be exposed to the direct action of the sand blast.

It is necessary that provision be made for removing the cleaned eggs and for replacing them with eggs that are to be cleaned, and also that the portion of the mat exposed for this purpose should not be exposed to the blast of either the sand or air, and the means for accomplishing this will now be described.

The baffle structure 3 is not extended throughout the entire circuit of the egg

supporting platform but terminates at the front portion of the machine so as to leave exposed an area of the platform sufficient to contain possibly half a dozen eggs, and 5 a shield 58 suitably conformed is placed between the terminals of the structure 3, this shield having an arcuate vertical portion 59 that extends downwardly in close proximity to the inner edge of the platform 10 19, as shown at Figure 12, and also a horizontal portion 60 that extends inwardly so as to overhang the sand and air blasts, and this shield is secured to a closure panel 61, which latter is removably secured to the 15 structure 2 so as to close an opening therein, designated by the numeral 62, and shown particularly at Figures 1 and 12, this panel being removed for the obvious purpose of examining the interior of such structure 2.

20 The inner wall of the portion 59 preferably has secured thereto and extending therefrom deflectors 63, which function to break up the swirling action of the air and sand, causing the latter to drop back into 25 the hopper and so opposing the swirling of the air that the latter will not materially increase the swirling tendency as it strikes the deflectors 21 and 21^a immediately beyond the shield 58.

30 The blast member 16 revolves in the direction indicated by the arrow in Figure 2, and therefore the air blast coming from the rear of the egg supporting and manipulating elements would have a strong tendency 35 to be felt to some extent by the operators that stand at the front of the machine and remove and replace eggs, and in order to save the operator from annoyance of this sort certain means is provided for preventing this, as will be readily understood from the following description.

Referring to Figures 1, 2 and 11, 64 are 40 gates each of which has an opening 65, the periphery of the gates being such that they fit snugly within the terminals of the baffle structure 3 and are secured therein. Extending rearwardly from each gate and coincident with the opening 65 is a hollow 45 circular hub-like member 66 which encloses and overhangs the egg supporting platform so that it will be clear that these gates with their hubs constitute tunnels at the ends of the structure 3, through one of which tunnels the cleaned eggs emerge while through 50 the other tunnel uncleaned eggs enter.

One of these tunnel-like structures is, of 55 course, exposed more or less to the air blast, and therefore this particular tunnel, which has been illustrated in detail at Figure 11, has a flexible and readily collapsible rubber 60 shed 67 secured to its hub 66 which shed will readily yield to the passage of the eggs but will always be forced toward the egg supporting platform by the action of the air, so that this shed is exceedingly serviceable

in preventing the currents of air from annoying the operators.

Integral with the terminals of the structure 3 is an arcuate rim 68 which acts as a closure to the front of the machine immediately outside the annular gear 22, and within this rim is a removable door 69 which is merely held in position by hook-like members 70 secured to the lower portion of the structure 3 and spaced therefrom, but this door while it may not be actually necessary, is nevertheless advantageous since its removal enables the operators to handle the eggs more conveniently.

The mat 20 exerts a grasping effect on the 80 eggs, and also is movable along the platform 19, and this last named characteristic is quite necessary, since, if an egg is broken during the cleaning operation, the operator then takes hold of the mat and pulls it 85 around until the particular locality where the egg was broken becomes available for cleaning purposes.

Since the rubber mat is not readily pulled around, it is preferred to equip this mat as 90 shown at Figure 8, where the mat is shown secured at its outer periphery to a metal annulus 71, so that with a mat of this sort the pulling around by the operator is greatly 95 facilitated.

What is claimed is:—

1. In an egg cleaning machine, the combination of a stationary annular egg supporting platform, a surrounding rotary ring having fingers extending above and across 100 said platform at predetermined intervals between which fingers the eggs on the platform are confined, means for slowly revolving the ring whereby the eggs are pushed by the fingers along the platform and throughout the circuit thereof, and centrifugally operating means having its axis of rotation concentric with that of said ring for creating 105 a sand blast that is discharged adjacent the inner periphery of said platform, whereby 110 said eggs will be subjected to the cleaning action of the sand.

2. In an egg cleaning machine, the combination of a stationary annular egg supporting platform, a rotary member surrounding said platform and carrying fingers which project above and across the platform whereby the eggs are pushed along 115 said platform throughout the circuit thereof, means for creating a sand blast and causing it to act adjacent the inner periphery of said platform against the eggs, and means for causing an air blast which is delivered from the rear of the ring and acts against the sand to drive the latter away from the 120 egg supporting and pushing elements after such sand has performed its function and has disseminated.

3. In an egg cleaning machine, the combination of a stationary annular egg sup- 130

- porting platform, a surrounding rotary ring having fingers extending above and across said platform at predetermined intervals between which fingers the eggs on the platform are confined, means for slowly revolving the ring whereby the eggs are pushed by the fingers along the platform and throughout the circuit thereof, means for causing a centrifugal sand blast having its 5 axis of rotation concentric with that of said ring and its effective discharge adjacent the inner periphery of said platform, whereby said eggs will be subjected to the cleaning action of the sand, and means for causing 10 a centrifugal air blast likewise having its axis of rotation concentric with that of said ring but with its effective discharge from the rear of said ring and against the sand, whereby the latter, after it has performed 15 its function and disseminated, will be driven inwardly.
4. An egg cleaning machine comprising a stationary annular egg supporting platform, a surrounding rotary ring carrying at intervals fingers which extend above and across said platform and terminate in angular extensions, a rotary blast member having radial ribs on its upper face and vanes near its periphery on its lower face, said 20 upper face adjacent said platform while the lower face communicates with an air space and leads beneath said platform to the rear of said rotary ring, a baffle structure extending beneath said platform and around 25 the ring and having a baffle plate portion that overhangs said platform, and means for revolving the blast member at a high speed and simultaneously revolving the ring at a low speed, whereby the eggs are subjected 30 to the action of the sand and the platform and adjacent parts kept clean of sand.
5. In an egg cleaning machine, the combination of a stationary annular platform, a mat loose thereon and having studs projecting therefrom, means for slowly driving the eggs throughout the circuit of said mat against said studs and retaining the eggs on the mat, means for causing a sand blast and subjecting the eggs to the action of such 40 blast, and means for clearing the eggs of sand.
6. In an egg cleaning machine, the combination of a stationary annular platform, a rubber mat loose thereon, and a metal annulus secured to said mat whereby the latter may be manually dragged around the platform.
7. In an egg cleaning machine, the combination of a baffle structure having an overhanging portion and provided with deflectors, a stationary annular egg supporting platform mounted within said structure and spaced therefrom, a rotary ring likewise supported by said structure and having spaced 50 fingers extending above and across said plat-
- form, and means for creating simultaneous sand and air blasts delivered respectively at the inner edge of said platform and beneath said platform and ring against said overhanging portion, whereby the disseminated sand will be blown inwardly.
8. In an egg cleaning machine, the combination of a stationary annular egg supporting platform, a rotary member carrying means for driving the eggs around the circuit of said platform, mechanical means for creating a centrifugal sand blast having its axis of rotation concentric with said platform and adapted to deliver the sand adjacent the latter for cleaning the eggs, 60 mechanical means for creating an air blast also having its axis of rotation concentric with said platform and adapted to deliver the air beneath the latter and in the rear of said member, a baffle structure beneath 65 and encompassing said member and platform and having a portion overhanging said platform, and means for controlling the air blast whereby it is caused to drive the sand away from the eggs and surrounding parts after said sand has performed its 70 cleaning function and become disseminated by contact with said overhanging portion.
9. In an egg cleaning machine, the combination of means for creating a sand blast, 75 a hopper for automatically delivering sand for said blast, means for supporting the eggs within the field of said blast, a chamber leading into said hopper, means for blowing the disseminated sand within said 80 chamber, and a screen device depending within said chamber whereby the sand is separated from dust and the latter blown 85 through the screen out of the machine.
10. In an egg cleaning machine, the combination of a stationary annular egg supporting platform, a rotary member surrounding said platform and carrying fingers which project above and across the platform whereby the eggs are pushed along 90 said platform throughout the circuit thereof, means for creating a sand blast and causing it to act adjacent the inner periphery of said platform against the eggs, means for creating an air blast that is delivered from the rear of said rotary member 95 and acts against the sand to drive the latter away from the egg supporting and pushing elements after such sand has performed its function and has disseminated, 100 and means for shielding the eggs and the adjacent parts from both of said blasts throughout a predetermined portion of the front of the machine with the eggs and their support exposed.
11. In a machine for cleaning eggs, the combination of a baffle structure having a base portion, a curved side portion and an overhanging portion, annular egg supporting 105 and manipulating means supported 110

- above said base portion and spaced therefrom and located beneath said overhanging portion, means for creating a centrifugal sand blast having its axis of rotation concentric with said egg supporting means and directed outwardly against the latter for cleaning the eggs, a sand hopper for supplying sand for said blast, means for creating a centrifugal air blast also having its 10 axis of rotation concentric with said egg supporting means and directed beneath and in the rear of the latter in opposition to the sand blast whereby the disseminated sand is blown inwardly away from said egg supporting means, and sand separating and cleaning devices which receive the sand thus blown and cleanse it of dust and dirt and permit the sand thus cleaned to fall into the hopper.
- 20 12. In an egg cleaning machine, the combination with a stationary annular egg supporting platform, means for creating a sand blast, means for pushing the eggs along said platform throughout the circuit thereof and 25 for simultaneously subjecting the eggs to the action of said sand blast, and means for turning the eggs at stated intervals during their travel along said platform.
13. A structure as in claim 1, in which 30 passive means are provided which cooperate with the fingers at stated intervals in turning the eggs during the travel of the eggs

throughout the circuit of the platform, whereby both ends of the eggs are subjected to the action of a sand blast.

35

14. In an egg cleaning machine, the combination of a baffle structure having spaced terminals at the front of the machine and provided with air deflectors, a stationary annular egg supporting platform mounted 40 therein and spaced therefrom, a rotary ring supported within said structure and carrying means for driving said eggs throughout the circuit of said platform, means for creating simultaneous sand and air blasts delivered respectively at the inner edge of 45 said platform and beneath the latter and ring against said overhanging portion, entrance and outlet tunnel-like structures respectively located within said terminals, 50 and a collapsible shed secured to the entrance tunnel.

15. An egg cleaning machine comprising means for supporting the eggs, means for subjecting them to the action of a sand 55 blast, means for impelling the eggs along said supporting means, and means for turning the eggs during the impelling thereof whereby all surfaces of the eggs will be subjected to said blast.

In testimony whereof I affix my signature hereto.

PERRY S. MARTIN.
